UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

KEYBOARD MECHANISM FOR TYPOGRAPHICAL MACHINES.

Application filed February 26, 1923. Serial No. 621,222.

To all whom it may concern:

Be it known that I, DAVID S. KENNEDY, a citizen of the United States, residing at Brooklyn, in the county of Kings and State 5 of New York, have invented certain new and useful Improvements in Keyboard Mechanisms for Typographical Machines, of which the following is a specification, reference being had therein to the accompanying drawing.

This invention relates to keyboard mechanisms, and more particularly to those of the kind now employed in the commercial linotype machine, or as illustrated in the U. S. 15 patent to P. T. Dodge, No. 530,931. In these keyboard mechanisms, the finger keys are connected through vertical actuating slides to trip dogs or triggers which, in response to manipulation of the keys, control 20 the action of horizontally disposed power-operated cam-yokes arranged to engage and actuate the matrix releasing devices, all as fully set forth in the said Dodge patent. To insure the proper operation of the keyboard 25 mechanism, it is essential that the actuating slides which connect the finger keys and trip dogs should be kept thoroughly clean and in good condition, as otherwise they are apt to stick or bind and thus interfere with the action of the power-operated 30 cam yokes. For these and other reasons, it is necessary at times to remove the actuating slides for inspection, cleaning or repair, the frequency of such removal depending 35 upon the conditions under which the machine is being used. In prior constructions, the removal of the actuating slides is difficult and troublesome and requires considerable time. As a matter of fact, it is 40 necessary to remove the entire keyboard mechanism from the machine and to dismantle it in part before complete access can be had to the actuating slides, this practice requiring the services of a skilled 45 mechanic or one entirely familiar with linotype construction. And, of course, the restoration of the keyboard mechanism to the machine involves corresponding difficulties and delays.

50 The present invention is intended to obviate the foregoing disadvantages and aims to provide a construction whereby the actuating slides may be quickly and easily removed from or applied to the keyboard mechanism as a unit, and this even when the

main keyboard frame is fixed in place in the machine. In accomplishing this result, specifically, the actuating slides are supported in and carried by a special subsidiary frame which is designed to be attached to 60 or detached from the main keyboard frame at will. The invention also contemplates the use of a safety device which will prevent the application or removal of the subsidiary frame except when the finger keys 65 are locked against actuation and with their rear ends depressed. These and other improvements will be fully set forth in the detailed description to follow.

In the accompanying drawings:

Fig. 1 is a side elevation, partly in section and partly broken away, of the keyboard mechanism of a linotype machine equipped with the present improvements;

Fig. 2 is a rear elevation of the improved 75 subsidiary frame, shown with its central portion omitted and with some of the actuating slides supported therein;

Fig. 3 is a top plan view of the keyboard mechanism, with the cam-yokes and their 80 driving rolls removed, and showing in particular the locking means for the finger keys and the safety devices which prevent the removal of the subsidiary frame at an improper time; and

Fig. 4 is an enlarged sectional view of a detail.

As usual, the keyboard mechanism comprises two series of horizontally disposed yokes or levers B arranged with their inner 90 ends in operative relation to the matrix releasing devices A and mounted at their opposite ends to rock about transverse pivot wires or rods B¹. Between their ends, the yokes B are provided with rotary cams or eccentrics 95 C, journaled thereto as at C¹ and adapted to be rotated by underlying power driven rolls D, there being one roll for each series of yokes. Normally, the cam-yokes rest upon angular trip dogs or triggers E which 100 support them at such height as the main- tain the cams C out of engagement with the rolls D, the cams in this position of the parts being held against rotary motion by their engagement with fixed stops C². When, 105 however, the trip dogs E are moved, the cam yokes B drop and disengage the cams C from the stops C², bringing the cams into contact with one or the other of the rolls D and causing the yokes to be reciprocated 110

in the usual manner. The trip dogs E are operated by a single series of vertical actuating slides F, formed at their upper ends with open notches f wherein the trip dogs 5 loosely engage, every other slide being connected to the trip dogs of one series, and the intermediate slides being connected to the trip dogs of the other series. The actuating slides F are in turn operated by 10 horizontal pivoted finger keys, or key levers G loosely engaged at their rear ends in open notches f' formed in the forward edges of the slides. The finger keys B, as usual are arranged in a plurality of rows or tiers 15 within a box-like casing G¹ presenting an inclined front plate G² and a vertical rear plate G³ both formed with elongated slots as shown, to guide the opposite ends of the key levers in their vertical movements. All of 20 the parts above described, with the exception of the escapement reeds A (which are sustained in the fixed framework of the machine), are supported either directly or indirectly in the main keyboard frame H presenting at the rear and at opposite sides two upright posts H¹. The foregoing parts and their mode of operation, except as hereinafter pointed out, are or may be the same 25 as embodied in the commercial linotype machine, or as illustrated in the Dodge patent before referred to.

As before stated, the present invention is directed to a construction whereby the actuating slides F may be quickly and easily 30 removed as a unit for inspection, cleaning or repair. Accordingly, said slides are supported in a subsidiary frame J detachably connected to the main keyboard frame H. In the present instance, the frame J is of 35 rectangular form and comprises top and bottom members J¹, J², and side or end members J³, J⁴, respectively, all secured together in the manner shown to make up a rigid unitary structure. In order to locate 40 the subsidiary frame in proper position within the main keyboard frame, the members J³ and J⁴ are made of angular form so as to fit against the inner and rear faces of the two upright posts H¹, and the latter 45 are provided with dowel pins J⁵ adapted to pass through corresponding openings formed in the laterally extending portions of said members. Any suitable means capable of being quickly released may be employed to hold the subsidiary frame in place, the means herein shown consisting simply of 50 a pair of screw bolts J⁶ passing loosely through holes or openings drilled through the upright posts H¹ and screwed into 55 threaded openings tapped in the laterally extending portions of the members J³ and J⁴. It will now be evident that to remove 60 the subsidiary frame, it is merely necessary to unscrew the bolts J⁶ and slip it off the 65 dowel pins J⁵ from the rear, the frame car-

rying with it the entire series of actuating slides F. In providing for their support in the frame J, the slides F are formed in their rear edges with elongated notches F¹ whose upper walls rest upon the top frame member J¹, against which they are held by a detachable comb plate J⁷ bearing against the forward edges of the slides (Fig. 1); and at their lower ends, the slides are formed with reduced portions F² arranged 70 between a pair of comb plates J⁸ detachably secured to the lower frame member J² (Fig. 4). As thus mounted, the slides are free to be raised and lowered within the subsidiary frame when it is in place but are 75 prevented from falling out of the frame when it is removed. 80

In the present embodiment, before removing the subsidiary frame J, it is necessary first to remove the rear series of cam-yokes B and their trip dogs E, as well as the rear power driven roll D. For this reason, these parts are all mounted in a removable subsidiary frame O detachably connected to the main frame H, as by means of screw bolts O¹, substantially as set forth in my prior Letters Patent No. 888,177. After the removal of the frame O with the contained parts, the subsidiary frame J is then free to be removed in the manner above described, see the dotted line showing in Fig. 1. It may here be remarked that if the keyboard mechanism comprised only a front series of cam-yokes (as might be the case), the subsidiary frame could be removed at once 90 without disturbing the yokes at all, seeing that the open notches in their forward edges would permit the slides to be automatically disengaged from the trip dogs and finger keys during the removal of the frame. The necessity for first removing the frame O, however, is unimportant, as this can be done almost instantaneously and without difficulty. 95

As a further feature of this invention, 100 means are provided to prevent the removal of the subsidiary frame except when the finger keys are locked against actuation and with their rear ends depressed. In carrying out this feature, it is proposed to make 105 use of the improved locking device disclosed in my prior Letters Patent Nos. 1,397,970 and 1,397,971. This locking device is in the form of a plate K slidably mounted upon the fixed front plate G² and formed with 110 elongated slots through which the forward ends of the finger keys G extend, the plate K thus being practically a duplicate of the plate G². As will be appreciated, in the forward or 115 inactive position of the locking plate K, its elongated slots are in registry with the corresponding slots of the fixed plate G², so that the finger keys are free to be depressed or actuated in the usual way (see Fig. 1); but when the locking plate is in its rearward 120 position, the elongated slots of the plate K are 125 shifted laterally so as to be out of registry with the corresponding slots of the fixed plate G², so that the finger keys are held in a depressed position and cannot be actuated. 130

or active position; its slots are out of registry with those of the fixed plate and present their lower end walls beneath and in engagement with the bottom edges of the 5 finger keys, which are thus locked against depression or actuation. In order to effect the depression of the rear ends of the finger keys, the plate K is arranged to move rearwardly to such extent that the lower end 10 walls of its slots pass beyond a mere locking position and act beneath the forward ends of the finger keys with a cam effect, that is to say, so as to raise such forward ends slightly and thereby depress the rear 15 ends. When the rear ends of the finger keys are thus depressed, they will stand clear of or out of engagement with the actuating slides F, which therefore are free to be removed from or applied to the keyboard 20 without any danger of interference with the finger keys. Adjustment of the locking plate K is effected by means of the cam plate K¹, as in the prior patents above mentioned.

25 Connected to and operated by the locking plate K is a pair of bell crank levers L pivoted, as at L¹, to opposite sides of the keyboard casing G¹. The longer arms of these levers are provided at their extremities with shields L² covering the fastening screws J⁶ which hold the subsidiary frame J in place. In the normal condition of the parts, as shown in Fig. 1, (i. e., with the locking plate K in its inactive position), the 30 shields L² completely cover the fastening screws J⁶ and prevent access thereto, but when the locking plate K is shifted to its active position, the levers L carry the shields L² downwardly to expose the screws, as indicated by the dotted lines in Fig. 1. In this latter condition of the parts, the subsidiary frame is free to be removed, the finger keys being locked and depressed as required. The 35 same conditions hold true, of course, in applying or restoring the subsidiary frame to the machine, this being permitted or prevented according to the position of the shields L² as determined by the adjustment of the locking plate.

40 The invention has been shown herein only in preferred form and by way of example and as applied to a keyboard mechanism of the class described, but obviously many changes and alterations may be made there- 45 in and in its mode of application, which will still be comprised within its spirit. It is to be understood, therefore, that the invention is not limited to any specific form or embodiment except in so far as such limitations 50 are specified in the claims.

Having thus described my invention, its construction and mode of operation, what I claim is, as follows:

55 1. In a keyboard mechanism of the class described, the combination of a series of

power-operated devices, key-controlled actuating slides governing the action of said devices, and a supporting frame carrying the actuating slides, the said frame with the contained slides being mounted for removal 70 or replacement as an independent unit.

2. In a keyboard mechanism of the class described, the combination with a series of power-operated cam-yokes, trip dogs therefor, finger keys, and actuating slides connecting the finger keys and trip dogs, of a separate supporting frame carrying the actuating slides and mounted so as to permit the ready removal or replacement of 75 said slides as an independent unit.

3. In a keyboard mechanism of the class described, the combination with a series of power-operated cam-yokes, trip dogs therefor, finger keys, and actuating slides connecting the finger keys and trip dogs, of a main frame giving support to the various parts, and a subsidiary frame carrying the actuating slides and detachably connected to the main frame.

4. In a keyboard mechanism of the class described, the combination with a series of power-operated cam-yokes, trip dogs therefor, finger keys, and actuating slides connecting the finger keys and trip dogs, of a main frame giving support to the various parts, and a subsidiary frame carrying the actuating slides and detachably connected to the main frame, the said subsidiary frame being removable bodily in a rearward direction for the purpose described.

5. In a keyboard mechanism of the class described, the combination with a series of power-operated cam-yokes, trip dogs therefor, finger keys, and actuating slides connecting the finger keys and trip dogs, of a main frame giving support to the various parts, a subsidiary frame carrying the actuating slides, means for locating the subsidiary frame in proper position with the main frame, and means releasable at will 105 for securing the subsidiary frame in such position.

6. In a keyboard mechanism of the class described, the combination with a series of power-operated cam-yokes, trip dogs therefor, finger keys, and actuating slides connecting the finger keys and trip dogs, of a main frame giving support to the various parts and presenting two upright posts at opposite sides, a subsidiary frame of rectangular form carrying the actuating slides and having its end members formed to fit over the upright posts, and means for detachably connecting the subsidiary frame to the main frame.

7. In a keyboard mechanism of the class described, the combination with a series of power-operated cam-yokes, trip dogs therefor, finger keys, and actuating slides connecting the finger keys and trip dogs, of a 130

- main frame giving support to the various parts and presenting two upright posts at opposite sides, a subsidiary frame of rectangular form carrying the actuating slides and having its end members formed to fit over the upright posts, dowel pins to locate the subsidiary frame in proper position within the main frame, and means for detachably securing the two frames together.
10. 8. In a keyboard mechanism of the class described, the combination with a front and a rear series of cam-yokes and trip dogs, finger keys, and actuating slides connecting the finger keys to the trip dogs of both 15 series, of a main frame giving support to the various parts, a subsidiary frame carrying the rear series of cam-yokes and trip dogs and detachably connected to the main frame, and a further subsidiary frame carrying the actuating slides and also detachably connected to the main frame.
9. In a keyboard mechanism of the class described, the combination with a series of power-operated cam-yokes, trip dogs therefor, finger keys and actuating slides connecting the finger keys and trip dogs, of a removable supporting frame carrying the actuating slides, and means to prevent the removal of said frame at an improper time.
10. In a keyboard mechanism of the class described, the combination of a series of finger keys, a locking device therefor, actuating slides operated by the finger keys, a removable supporting frame carrying the actuating slides, and means for preventing the removal of the supporting frame except when the locking device is in active position. 30
11. In a keyboard mechanism of the class described, the combination of a main frame, a series of finger keys, a locking device therefor, actuating slides operated by the finger keys, a removable subsidiary frame carrying the actuating slides, releasable means for fastening the subsidiary frame to the main frame, and means controlled by the locking device to prevent access to the releasable fastening means except when the locking device is in active position. 35
12. In a keyboard mechanism of the class described, the combination of the finger keys G, the actuating slides F, the main keyboard frame H, and the removable subsidiary frame J carrying the actuating slides F, all substantially as shown and described. 40
- In testimony whereof, I have affixed my signature hereto. 45

DAVID S. KENNEDY.
